HEATING SYSTEM.

1,226,694.

Specification of Letters Patent. Patented May 22, 1917.

Application filed January 10, 1916. Serial No. 71,322.

To all whom it may concern:

Be it known that I, RAY S. PORTER, a citizen of the United States, residing at Minneapolis, in the county of Hennepin and 5 State of Minnesota, have invented certain new and useful Improvements in Heating Systems, of which the following is a specification.

My invention relates to steam and vapor 10 heating systems and has for its object to provide a steam feed line and a return air and water line both of which issue from the top of the boiler. In the air line I provide a seal to which the remote end of the steam 15 line is connected, so that both the water in the water return line and the condensation in the steam line return to the boiler through this seal. A most important feature of this arrangement is that the water 20 level in the boiler or generator will not fluctuate under varying pressure, as so frequently and injuriously happens where boilers follow the usual construction in which the return pipe enters at the bottom of the 25 boiler. This fluctuation is due to sudden rises of pressure within the boiler which forces the water out of the boiler through the return pipe. Of course such a result 30 is impossible in the construction of my invention. A second object is to provide the water return line with a drum for separating the air from the water prior to its entering the boiler and a vent for allowing the 35 air to escape. A third object is to provide said drum with a passageway for allowing the water in the seal to be temporarily displaced when the pressure in the boiler rises to a certain height, thus allowing the superfluous steam in the boiler to escape 40 through the vent without removing any water from the system or without draining the boiler.

The full objects and advantages of my invention will appear in connection with 45 the detailed description thereof and are particularly pointed out in the claims.

In the drawings, illustrating the application of my invention in one form,—

Figure 1 is a diagrammatic view of my 50 improved form of vapor heating system. Fig. 2 is a longitudinal section of the separating drum shown in Fig. 1. Fig. 3 is a modified form of separating drum.

An ordinary boiler 10 adapted for vapor 55 heating systems is indicated in Fig. 1. This

boiler is shown having a steam dome 11 and is connected with a flue 12.

From the top of the dome 11 issues a steam line 13 which may be of any suitable size to accommodate the number of radiators installed. Parallel to steam line 13 is a return line 14 which conducts away the air and water present in the radiators. Both of these lines may be suitably inclined in the usual manner, being highest where line 13 leaves the boiler and gradually sloping downward. At suitable intervals on these two lines risers 15, 16 and 17, 18 may be provided to communicate with radiators 19 and 20. The steam risers 15 and 17 will, as customary, be connected with the tops of the radiators 19 and 20 and may be provided with graduated rod valves 21 and 22 for regulating the amount of steam vapor required. The returns 16 and 18, as shown, 70 are connected with lower portions of the radiators, as is also a common method.

Above the steam dome 11 in the vicinity of boiler 10 is situated a drum 23, shown in detail in Fig. 2. A cylindrical casing 24 80 is provided with caps 25 and 26 threaded to receive pipes 27 and 28. Within cylinder 24 is attached a pipe 29 in direct communication with pipe 28 and terminating near cap 25 in an elbow 30. The return 85 water and air line 14 enters the cylinder 24 opposite the open end of the elbow 30. Pipe 29 is provided with a small aperture 31 near the cap 26. When water and air enter the cylinder 24 through the pipe line 14 the air 90 escapes through pipe 27 and the water through aperture 31 flows back to the boiler through pipe 28. As seen in Fig. 1, the pipe 27 is connected with the flue 12 through a pipe 32. The suction present in the flue 95 aids in withdrawing the air and condensed water from pipe line 14 and so quickens the action of the device by causing the system to operate at a partial vacuum.

Pipe 28 extends downward from drum 23 100 and is connected with a short pipe 34 to which is connected an upwardly-extended pipe 35 communicating with the top of the steam dome 11. All the water which is returned to the boiler passes through pipes 28, 105 34 and 35, which, as noted, are arranged like a U and form a seal so that with a normal pressure the steam in the boiler does not escape through the pipe 35.

The steam pipe 13 is provided at its upper 110

portion adjacent the junction with a downwardly-extended pipe 36 with an automatic air valve 37. This valve operates to release all air in the main steam or vapor line, the air in the radiators and branch lines passing through the return line 14 and releasing through pipe 32. It follows that immediately upon the formation of vapor or steam the air in the entire system will be quickly expelled ahead of the incoming vapor and the system will thereafter work at a partial vacuum due to the suction in the flue 12, causing complete and efficient circulation.

15 Drum 23 serves a double purpose, namely as a safety device as well as an air-separating device. When the pressure in boiler 10 increases above a certain point the water in the seal will be forced upward through pipe 29 and into the space between cylinder 24 and pipe 29. This will occur until pipes 34 and 35 have been sufficiently drained, when the excess steam in the boiler will flow through them and into the flue 12 through the vent 32. When enough steam has escaped to decrease the pressure, the water will flow down again through hole 31 to again fill up the seal. It hence becomes evident that the storage capacity of the cylinder 24 must be great enough to hold the water displaced from the seal, so that the water will not fill the vent 27 and prevent the steam from escaping.

In practice it has been found that the device operates efficiently when pipe 36 has about twice the diameter of pipes 28 and 35. The elbow 30 on pipe 29 directs the water discharged from said pipe against casing 24 and prevents it from entering the vent 27 and the return line 14.

40 A modified form of drum is shown in Fig. 3 in which a body 40 is provided with caps 41 and 42, the same as in Fig. 2. The safety outlet pipe 38 is, however, set to one side in cap 41 and the vent pipe 43 is set in the opposite side of cap 42, and pipe 38 extends well up to the cap 42. This prevents the water discharge through pipe 38 from entering either pipe 42 or the water line 44, and serves the same purpose as the elbow 30 in the preferred form.

45 In other systems similar to my invention the objects of my invention have been provided in more or less cumbersome and unsatisfactory ways, employing complicated and delicate devices which were difficult to regulate and adjust. My invention employs nothing but pipes and pipe fittings and the separating drum. This simplifies the installation and cost of the system and renders it entirely automatic, requiring no attendance further than to fire the boiler. Due to the fact that both the water line and the steam line of the system issue from the top 50 of the boiler, the crown sheet of the same

can never become dry, as no water is displaced from the boiler other than by evaporation, so that injury to the boiler is improbable. The pipes 35 and 28 may be made any desired length, and so the device 70 will operate very accurately at any desired pressure.

I claim:

1. A heating system comprising a generator for steam or vapor, a system of feed 75 and return pipes each opening into the top of the generator above the water line therein, and a water trap extending to a point below said water line with which both the feed and return flow pipes are connected and to which the condensate from both lines is discharged.

2. A heating system comprising a generator for steam or vapor, a system of feed 85 and return pipes each opening into the top of the generator above the water line therein, and a water trap extending to a point below said water line with which both the feed and return flow pipes are connected, said feed and return flow pipes being 90 severally connected with the trap at respectively different points.

3. A heating system comprising a generator for steam or vapor, a system of feed 95 and return pipes each opening into the top of the generator above the water line therein, a water trap extending to a point below said water line with which both the feed and return flow pipes are connected, and a blow-off pipe connected with the trap 100 and open to atmosphere.

4. A heating system comprising a generator for steam or vapor, a system of feed 105 and return pipes each opening into the top of the generator above the water line therein, a water trap extending to a point below said water line with which both the feed and return flow pipes are connected, a blow-off pipe connected with the trap 110 and open to atmosphere, and a chimney having a flue with which the waste pipe of the generator and the blow-off pipe connect.

5. A heating system comprising a generator for steam or vapor, a feed pipe opening 115 from the top of said generator, and having branches communicating with the several radiators, a return pipe in communication with the several radiators, said return pipe also entering the generator at the top thereof, and a coil of said pipe being formed to 120 extend below the water line of the generator and providing a water trap in said return pipe.

6. A heating system comprising a generator for steam or vapor, a feed pipe opening 125 from the top of said generator, and having branches communicating with the several radiators, a return pipe in communication with the several radiators, said return pipe also entering the generator at the top there- 130

- of, a coil of said pipe being formed to extend below the water line of the generator and providing a water trap in said return pipe, and a section of pipe connecting said 5 feed pipe with the lower portion of said trap.
7. A heating system comprising a generator for steam or vapor, a feed pipe opening from the top of said generator and having 10 connections to the radiation members of the heating system, a return pipe having connections with said members, an expansion chamber in connection with said return pipe, and a section of pipe connected at one end 15 with the expansion chamber and at the other end with the top of the generator and extending below the water line of the generator to form a water trap below said water line.
- 20 8. A heating system comprising a generator for steam or vapor, a feed pipe opening from the top of said generator and having connections to the radiation members of the heating system, a return pipe having 25 connections with said members, an expansion chamber in connection with said return pipe, a section of pipe connected at one end with the expansion chamber and at the other end with the top of the generator and extending 30 below the water line of the generator to form a water trap below said water line, and a blow-off pipe connected with the top of said expansion chamber.
- 35 9. A heating system comprising a generator for steam or vapor, a feed pipe opening from the top of said generator and having connections to the radiation members of the heating system, a return pipe having 40 connections with said members, an expansion 45 chamber in connection with said return pipe, a section of pipe connected at one end with the expansion chamber and at the other end with the top of the generator and extending below the water line of the generator to form a water trap below said water 50 line, an extension of said last named section of pipe within the expansion chamber and opening close to the top thereof, said extension being provided with small openings at the bottom of the expansion chamber, and a 55 blow-off pipe connected with the top of the expansion chamber.
10. A heating system comprising a generator for steam or vapor, a feed pipe opening from the top of the generator and having 60 connections to the radiators of the heating system, a return pipe having connections with said radiators, a water trap connected at one end with the top of the boiler and at the other end with the flue of a chimney adapted to counterbalance the pressure 65 in the boiler, means for receiving the water in said trap when the boiler pressure rises above normal, means for permitting the water in said receiving means to drain back 70 into the trap after the superfluous steam in the boiler has been blown into said flue, and connections between said feeding and return pipes and said trap for returning the condensate from both of said lines to the boiler 75 through said trap.

In testimony whereof I affix my signature in presence of two witnesses.

RAY S. PORTER.
